US00D941780S

(12) **United States Design Patent** (10) **Patent No.:** **US D941,780 S**
Buck et al. (45) **Date of Patent:** **** Jan. 25, 2022**

(54) **CONTACT WAFER**

(71) Applicant: **Samtec, Inc.**, New Albany, IN (US)

(72) Inventors: **Jonathan E. Buck**, New Albany, IN (US); **John A. Mongold**, New Albany, IN (US)

(73) Assignee: **SAMTEC, INC.**, New Albany, IN (US)

(**) Term: **15 Years**

(21) Appl. No.: **29/725,389**

(22) Filed: **Feb. 25, 2020**

Related U.S. Application Data

(63) Continuation of application No. 29/652,017, filed on Dec. 20, 2018, now Pat. No. Des. 881,133.

(57) **CLAIM**

The ornamental design for contact wafer, as shown and described.

DESCRIPTION

FIG. 1 is a top, front, and right side perspective view of a contact wafer showing our new design;

FIG. 2 is a bottom, back, and left side perspective view thereof;

FIG. 3 is a front view thereof;

FIG. 4 is a back view thereof;

FIG. 5 is a left thereof;

FIG. 6 is a right view thereof;

FIG. 7 is a top view thereof; and,

FIG. 8 is a bottom view thereof.

The broken lines in the drawing views are included to show portions of the contact wafer that form no part of the claimed design.

1 Claim, 8 Drawing Sheets
